UNITED STATES PATENT OFFICE.

JOHN STEPHENSON, OF NEW YORK, N. Y.

TROLLEY-BRIDGE.

SPECIFICATION forming part of Letters Patent No. 424,374, dated March 25, 1890.

Application filed February 4, 1890. Serial No. 339,145. (No model.)

To all whom it may concern:

Be it known that I, JOHN STEPHENSON, a citizen of the United States, residing at New York, in the county and State of New York, have invented certain new and useful Improvements in Trolley-Bridges, of which the following is a specification.

The propulsion of tram-cars by electricity has commanded a new class of mechanical devices embodying the connection of the car-propelling mechanism with an overhead electric conductor by means of a trolley at the end of an arm jointed to a base or support which is located centrally upon and fastened to the car-roof.

A tram-car roof is ordinarily a light and frail structure designed only to protect passengers from wind and storms, and the practice of fastening trolley-supports to the roofs has resulted in the rapid destruction or injury of the latter. Further, the roof, owing to its light construction and to its being supported only at the edges, is easily put in vibration by the movements of the trolley, producing a drumming or humming sound, which is disagreeable to the passengers, while the movements affect the fastenings of the trolley-support and chafe the roof-covering, causing decay and leaks.

My improvement consists in supporting the parts connected with the trolley by a bridge, which consists of a plank, frame, or other supporting structure placed above contact with the car-roof, and which is supported by the end or side walls of the car-body, accordingly as it is of greater or less length, as fully set forth hereinafter, and as illustrated in the accompanying drawings, in which—

Figure 1 is a side elevation of the upper portion of a tram-car embodying my improvement. Fig. 2 is an end elevation of Fig. 1 in part section. Fig. 3 is a detached view showing the bridge-post and support. Fig. 4 is a side view of the upper part of a car, showing the bridge supported from the side walls. Fig. 5 is an end view of Fig. 4. Fig. 6 is a detached view showing the rafters and roof-supports of the construction illustrated in Figs. 4 and 5. Fig. 7 is an enlarged detached view showing one of the rafters, bridge-post, and connections. Fig. 8 is the view of the top of a car in part section, illustrating an

other form of bridge-support. Fig. 9 is an end view of Fig. 8. Fig. 10 is a detached view showing the connection between one of the 55 roof-battens and the side top rail. Fig. 11 is a side view of Fig. 10. Fig. 12 is a side view illustrating another form of support. Fig. 13 is an end view of Fig. 12.

Of the various methods of constructing the 60 trolley-bridge I prefer that in which the end walls A of the car-body shall support the bridge, which, as shown, is a plank B, without any intervening contact of the plank with any part of the car structure. Such a structure is illustrated in Figs. 1 and 2, in which is shown as placed across the crown of the arch of each end wall a metal arch or base plate C, with its end extending each way sufficiently to secure a good bearing for the 70 plate on the end top rails s of the car-body. The metal arch-plate thus secured to the body has connected to its upper surface shorter post base-plates 1, each with a standing post 2, which extend through openings in 75 the end of the bridge-plank B, and between each end of the plank and each plate 1 is placed a spring 3, which surrounds the post, on which springs rests the bridge-plank, and on each post above the plank is placed another 80 spring 4, which is held in place by a nut 5 screwing onto the end of the post. At any suitable point upon the bridge-plank is secured the base J, to which is jointed the lower socket-piece D, supporting the rod 6, that is 85 connected with the trolley. This construction not only secures the best security to the bridge, but also secures a base of the requisite strength to support the parts connected with the trolley, while the bridge and the supporting-springs absorb the vibrations, and the connection of the same to the walls of the car prevents the vibration from being imparted to the roof and relieves the car from the noise and motion of the trolley.

Where it is desirable to shorten the bridge, the latter is supported from the side walls, as illustrated in Figs. 4 to 10. Thus the bridge may be shortened by adding for each end of the bridge-support B a bridge-rafter 7, bearing on the roof-boards, with its ends secured to the top rails 8 of the side walls of the car-body, as shown in Figs. 4, 5, 6, and 7. In this construction there is upon the upper surface

of the roof a cross-rafter 9 of such construction as may be suitable for carrying the ends of the shortened bridge-plate and supporting bridge-posts 2 and springs 3 4, whereby the 5 plank is connected to the car, but free from contact with the roof except at such end supports. The ends of the bridge-rafter 7 may be secured to the side top rails by framing into the latter, as usual, or by knee-plates 12, 10 as shown in Figs. 5 and 6.

In the construction illustrated in Figs. 8 to 11 there are at proper distance apart, according to the length of the bridge B, two roof-battens 13, of wood, outside the car-roof, but 15 conforming to its shape, each placed above a rafter 14, with the roof-boards and cotton-duck intervening between the battens and the roof-rafter, the whole secured together by bolts 15, forming a stiff arch, with its ends 20 secured to the top rails 8 of a car-body. Above the battens are bridge-blocks 16, of proper shape to support the base-plates of the bridge-posts 2, upon which are the springs 3 4, holding 25 the ends of the bridge, as before described.

25 In the construction illustrated in Figs. 12 and 13 there are desirably located outside and above contact with the roof, except over the side walls, two arched bars 17, of metal or wood, with their ends lodged in holders 18 of 30 suitable form, the holders being secured above and to the side top rails 8 of a car-body. Each arch-bar may have on its crown a bearing 19, with fixtures suitable for holding the bridge, as before described, or in any other 35 suitable manner.

Without limiting myself to the precise construction and arrangement of parts shown, I claim—

1. A car with a trolley-bridge over the crown 40 of the roof, supported directly or indirectly by the walls of the car-body, and the bridge elevated sufficiently to be free from contact with the car-roof, substantially as described.

2. A car with a trolley-bridge above and 45 out of contact with the car-roof and supported by the end walls of the car-roof and fastened to the end top rails thereof, substantially as described.

3. A car with trolley-bridge supported on 50 the car end walls by metal plates secured to the end top rails of the car-body, the plates

having vertical posts to receive the ends of the trolley-bridge and supporting the same sufficiently high to prevent it from contacting with the car-roof, substantially as described. 55

4. A car with the ends of the trolley-bridge plank on posts secured to the end walls of the car-body, the posts having on them springs on which the bridge rests free from contact with the car-roof, substantially as described. 60

5. A car with the ends of the trolley-bridge plank on posts secured to the end walls of the car-body, the posts having on them springs on which the bridge ends rest, and above the ends springs intervening between 65 the bridge and compressing-nuts on the post-heads, substantially as described.

6. A car with a trolley-bridge supported by arches or structures transverse to the car-body, having the ends of the arches secured 70 to the side walls of the car and the bridge-plank free from contact with the car-roof, substantially as described.

7. A car with a roof having rafters of special strength supporting and receiving the 75 fastenings of cross rafters or battens above the car and carrying a trolley-bridge without the same contacting with the car, substantially as described.

8. A car with arch-bars supporting a bridge 80 and extending above and free from contact with the car-roof, except that the ends of the bars are secured to proper fastenings to the side top rails of the car-body, neither bars nor bridge contacting with the car-roof, except at 85 the end holders of the bars, substantially as described.

9. An electric-motor car with a trolley-bridge consisting of a plank above its roof, with the ends of the plank on posts, having 90 springs intervening between the plank and the car-roof, substantially as described.

10. An electric-motor car provided with a trolley-bridge and having springs above and below the bridge, substantially as described. 95

In testimony whereof I have signed my name to this specification in the presence of two subscribing witnesses.

JOHN STEPHENSON.
